UNITED STATES PATENT OFFICE.

JOHN THOMSON, OF NEW YORK, N. Y.

ELECTRIC ZINC-FURNACE WITH INTEGRAL COMPOUND RESISTORS AND COMPOUND CONDENSERS.

1,086,416.

Specification of Letters Patent. Patented Feb. 10, 1914.

Application filed January 2, 1913. Serial No. 739,793.

To all whom it may concern:

Be it known that I, JOHN THOMSON, a citizen of the United States, and a resident of the borough of Manhattan of the city of New York, in the county and State of New York, have invented certain new and useful Improvements in Electric Zinc-Furnaces with Integral Compound Resistors and Compound Condensers, of which the following is a specification, reference being made to the accompanying drawings, forming a part thereof.

This invention relates to the metallurgy of zinc, having for its object the production of zinc-fume by thermo-chemical reaction and the subsequent condensing of said fume to liquid metal.

A description of the particular means for attaining the desired results and such an elucidation of the general principles applicable thereto as seem necessary for a complete disclosure of the invention are set forth in this specification, reference being had to the accompanying drawings forming a part of said specification and in which drawings a certain specific embodiment is illustrated.

In said drawings Figure 1 is a transverse center section of a combined furnace and condenser taken on the line A of Fig. 2, the charge and resistor having been removed from the upper or right hand portion of the apparatus. Fig. 2, on the lower or left-hand side of its center line, is a longitudinal center section, as B or B', of Fig. 1, and on the upper or right-hand side of its center line it is a side elevation to the plane D, D, and a center section from thence through either of the condensers, as C, or C', and Fig. 3 is a diagrammatic section illustrating a detail of the operation.

This furnace is particularly intended for the reduction of oxid-of-zinc combined with carbon as the reagent, whereby when adequately heated substantially the following representative reaction ensues, namely:

If pure ZnO and C are used in precisely correct relative proportions then the answer of the above formula is an exact expression of the result in that all of the charged material would be volatilized as zinc-fume and monoxid of carbon and in which case there would be no residue. Such conditions, how-

ever, do not obtain in commercial practice as more or less of inert residual matter will remain depending upon the purity of the materials employed and hence the formula becomes simply representative as above 60 stated. The presence of residual matter in even small quantities is a cause of difficulty in realizing the desired result.

The heat necessary for the decomposition of the charge may be derived either from a 65 superposed rod-resistor or from an underlying bed of carbon resistor or from both.

H is the rod-resistor disposed along the longitudinal center of the furnace, its ends being in contact with terminals 4 which are 70 suitably connected to the source of power and I is the bed of carbon resistor which is also interpolated between the terminals 5. Each of the aforesaid resistors may be separately electrified or they may be operated 75 in parallel or in series or the bed of carbon resistor may be incited on a shunt derived from the rod-resistor circuit. The rod-resistor is supported upon two series of refractories 6 beneath which are a series of ports 80 7 for stoking the charge material P contained in side galleries 8. Suitably supported steel channels 10 constitute means whereby continuous openings or slots 12 may be provided through which bars may 85 be introduced for effecting the stoking. This channel construction also provides for or permits the quick lifting off and ready removal of the side-walls supported thereupon thereby exposing when removed all of 90 the brick-work which normally underlies the walls on the channels.

The slots 12 may be closed by free bricks, as 10^a, when not necessarily open for stoking the charge. 95

The bed of carbon resistor is sustained by a series of spaced grate-bars as 13, which rest on ledges 13^a, formed in a shallow tamped casing R and beneath the grating is a sump n in which inert residual matter 100 as 14 is collected. In the sides of the casing are a series of lateral openings or ports 15 in the same plane as that of the grate-bars but each of which is in line with the spaces 16 between the said bars. Part of these 105 ports lead to the right and a part to the left to the free spaces or chambers e, e' of the condensers J, J' that are located alongside of the tamped casing R. The pillars 17 which divide the ports are preferably of 110

about the same width as the ports whereby when the charge-material is stoked in and upon the face of the bed of carbon resistor it will lie in ridges, as see Fig. 3, leaving about equal widths of the bed exposed and in fact sub-dividing the bed of carbon resistor into a series of transverse zones.

The operation may be in several different ways for example in any of the following several or joint manners: First, the charge may be decomposed by radiated heat from the rod-resistor as indicated by the arrows 18, Fig. 3, secondly, the charge may be decomposed by conducted heat derived from the bed of carbon resistor; thirdly, the charge may be decomposed by the joint action of both resistors, each imparting about an equal proportion of the total heat energy required, and, fourthly, the charge may be decomposed by the joint action of both resistors with one imparting a greater amount of heat energy than the other. What is so far deemed the preferred mode of operation is to supply current to the resistors so that normally the entire mass of the bed of carbon resistor will be heated to a temperature of say 2000° F. and so that the rod-resistor will have a temperature of about 2400° F. When these conditions are realized the charge is stoked as desired and decomposed by heat derived principally from the rod-resistor. The heat from this rod-resistor flows both to the ridges of charged material and to the exposed portions of the carbon bed. The inert residual matter may sift or percolate by gravity down through the carbon bed and into the sump as indicated by the arrows 19, and the volatilized products of the reaction will also flow directly down and through the said bed to the grating spaces from whence it flows through the ports as in the manner indicated by arrows 20. In this wise one of the chief functions of the carbon bed is to eliminate by a secondary reaction should such be required, any pernicious oxidizing agents and thereby deliver "clear" fume and gas into the condensing chambers. But the carbon bed will also somewhat act from heat imparted thereto by the rod-resistor to produce a certain proportion of the reaction by direct conduction of its acquired heat to the charge. Another mode of working is to impart the major portion of the energy through the rod-resistor with a certain minor portion from the bed of carbon resistor. Thus, if the two resistors are maintained at about the same temperature the reacting surfaces of both will be entirely utilized for useful effect and because of the fact that the condensers and the charge-material in the ports and galleries largely "blanket" the sides of the resistors the only loss of energy of any significance will be that emitted to and conducted away from the sump.

It will be perceived that if the carbon bed requires renewals this can readily be supplied by stoking, through the ports.

The fume and gas after reaching the condensing chambers thence flows downwardly through batteries comprising spaced, cross-stacked and preferably staggered plates as 22, 22^a and also comprising layers of broken carbon as V, to baths of molten zinc 23 and thence through right and left hand ports 24, 25, to flues or chambers T, T'. These layers of broken carbon V may be of such character as retort-carbon or pieces of broken carbon plates or rods and serve in the nature of a relatively thin filter. This "filter" is preferably situated near to the bottom of the battery and hence the volume of zinc fume which passes therethrough will be much less than that of the accompanying monoxid of carbon. Carbon terminals may be employed so that said filter may be operated as an electric resistor whereby the condenser as a whole may be preliminarily heated; whereby the liquid zinc in the bottom of the condenser may be preliminarily heated if desired and whereby the temperature within the condenser may be controlled or maintained during a period of intermission.

Another feature of the invention consists in placing two rows of supporting plates, 26, 27, to form three sub-flues or chambers, namely, the right and left flues or chambers T, T' and the central flue or chamber Y, all of which are disposed beneath the sump of the resistor casing. The supporting plates do not extend the full length of the flues but have openings as 28 at each end. Thus the inflowing residual gas enters the central portions of the chamber T and T', deflect right and left, pass through the openings 28 again deflect right and left whereby the streams flow toward each other and finally together pass out through the center tube 29 and thence to the underground or other suitable duct leading to atmosphere.

If desired a small pipe or pipes as 30, may be introduced to the spaces above the baths for educting a small quantity of CO and burning it to CO₂, as a test-flame.

Due to the above construction any uncondensed fume passing into the central flues or chambers through which the velocity of flow will be quite low, may be collected in the form of metal or as "blue-powder", while the heat contained in the gas serves to conserve the heat in the sump.

A system of circulation may be supplied either for imparting or subtracting heat to or from both zinc baths by causing a heating medium or cold air as the case may be, to enter one end of the underlying flue L, traversing its length then flowing through a connecting flue or pipe as 31, again along the length of the complementary flue, L' and thence to atmosphere as by the tube 32.

The improvements herein set forth are not limited to the precise construction and arrangement shown and described and they may be embodied in various forms and modifications without departing from the spirit and scope of the invention.

What I claim is:

- In an electric furnace a rod resistor and a broken carbon resistor between which the charge is located.

- In an electric furnace a rod resistor above a broken bed of carbon upon which the charge is located.

- An electric furnace having a reaction chamber provided therein, with a rod resistor and a bed of carbon resistor, between which resistors the charge is located.

- An electric furnace whose reaction zone is provided with a rod resistor which acts upon the upper portion of the charge, and a broken carbon resistor which acts upon the lower portion of the charge.

- In an electric zinc furnace, a resistor, acting upon the charge by radiated heat, and another resistor acting upon the charge by conducted heat, the charge being supported between the resistors while being acted upon thereby.

- In an electric zinc furnace a bed of carbon resistor serving as a support for the charge and an overlying-rod resistor for acting upon the said charge by radiant energy.

- In an electric zinc furnace a rod-resistor overlying a bed of carbon resistor with a charge interposed therebetween, all of the products of the reaction passing down through the said carbon bed.

- In an electric zinc furnace, a rod-resistor, an underlying bed of carbon resistor supported by spaced grates, a sump beneath the said grates, lateral ports in line with the grate spaces and a condenser or condensers connected to the said ports.

- In an electric zinc furnace, an overlying rod-resistor, and underlying bed of carbon resistor and a series of ports in the plane of the space between the two said resistors through which the charge is stoked upon the face of the carbon bed.

- In an electric zinc furnace, an overlying rod-resistor, an underlying bed of carbon and a series of ports in the plane of the space between the two through which the charge is stoked upon the face of the carbon bed.

- In an electric zinc furnace, an overlying rod-resistor and an underlying bed of carbon resistor, either or both of which may be electrically heated to similar or dissimilar temperatures.

- In an electric zinc furnace, an inclosed resistor having adjacent galleries defined by side-walls beneath which are continuous openings or slots in communication with the bottoms of said galleries.

- The combination with a source of supply of zinc fume, or zinc fume and gas of a condenser or condensers having a battery of cross-stacked members and one or more interposed layers of broken carbon.

- An electric furnace and condenser having a reaction-chamber sump and a plurality of flues disposed beneath the said sump which are arranged to receive residual gas or gases from the said condenser or condensers.

- An apparatus of the class described comprising in combination a rod-resistor, an underlying bed of carbon resistor, means for inserting charge-material between the said resistors, openings or ports for permitting the escape of the volatilized products of the reaction to a condenser, or condensers, and a sump for collecting the inert residual products of the reaction.

- In an electric zinc furnace, a bed of carbon adapted to be supplied upon its upper surface with charge-material in separated transverse ridges, and an overlying rod-resistor whose radiant energy acts upon the said ridges and also upon the exposed intervening spaces of the bed.

This specification signed and witnessed this 31 day of December, A. D. 1912.

JOHN THOMSON.
